UNITED STATES PATENT OFFICE.

FRANK HUMPHREYVILLE, OF ATLANTIC CITY, NEW JERSEY.

TOY ROCKER-CARRIAGE.

1,354,400.

Specification of Letters Patent. Patented Sept. 28, 1920.

Application filed November 12, 1919. Serial No. 337,432.

To all whom it may concern:

Be it known that I, FRANK HUMPHREYVILLE, a citizen of the United States, and resident of Atlantic City, Atlantic county, 5 and State of New Jersey, have invented a new and Improved Toy Rocker-Carriage, of which the following is a full, clear, and exact description.

This invention relates to wheel toys and 10 has reference more particularly to a toy which may be used by children either as a carriage or as a rocker.

The object of this invention is to provide a wheel toy which will be inexpensive to 15 manufacture, easy to operate, and highly amusing to children.

Reference is to be had to the accompanying drawing forming a part of the specification in which it is understood that the drawing 20 is merely illustrative of one example of the invention and in which,

Figure 1 is a side elevation of the toy adjusted for use as a carriage.

Fig. 2 is a rear elevation of the toy shown 25 in Fig. 1.

Fig. 3 is a side elevation of the toy adjusted for use as a rocker.

Fig. 4 is a fragmentary view showing the 30 means for vertically adjusting the front steering post.

Referring to the accompanying drawing by numerals, 10 indicates the seat of the rocker-carriage which is supported by a suitable frame work consisting of a pair of 35 horizontal members 11, a pair of rockers 12 and legs 13 and 14 connecting the members 11 and the rockers 12. Rotatably mounted in the seat 10 adjacent the leg 14 is a steering post 15 provided on its lower end with 40 a forked member 16, said member supporting a wheel 17 of any suitable construction between its legs by means of an axle 18. The steering post 15 is slidable axially in the seat 10 so that same may be adjusted ver- 45 tically in various positions, and is provided with a plurality of annular grooves 19. A slide 20 is mounted on the seat 10 adjacent the post 15 and is provided with a forked end 21, said end being arranged to engage 50 any desired annular groove 19 so as to fix the steering post in any desired vertical position. The other end of the slide 20 is provided with a laterally extending shoulder 22 which serves as a handle by which 55 the slide 20 can be moved toward or away from the steering post. The slide 20 is also

provided with a slot 23 through which passes a thumb screw 24, said thumb screw being threaded in the seat 10 and serving to fix the slide 20 in any desired position and especially to fix said slide so that its forked end 21 fixes the post 15 in some desired vertical position. At the top of the steering post 15 is fixed any ornamental member 25 such as the horse head shown in the drawings. A 60 rod 26 passes laterally through the head 25 and serves as a handle so that when a child is sitting on the seat 10, he may rotate the steering post 15 in the seat 10 by means of said rod thereby steering the carriage in any 65 desired direction as he propels it along the ground. Passing laterally through the lower ends of the legs 14 is a rod 14^a which extends out a certain distance on each side of said legs so that when the toy is used as a 70 rocker, the child may place his feet on said rod. A plurality of pairs of horizontal holes 27 extend through the legs 13 so that a hinge pin 28 may be journaled in one pair 75 of said holes. The hinge 28 pivotally supports a standard 29 which has journaled at its lower end an axle 30 on each end of which is rotatably mounted a wheel 31. The rod 28 may be placed in any pair of the 80 holes 27 so that the wheels may be adjusted 85 in various vertical positions relative to the seat 10. A laterally extending member 32 is fixed between the rear end of the rockers 12 and serves as a stop to limit the rotation of the standard 29. A pair of crank shaped 90 fasteners 33 are rotatably mounted on the member 32 so that when said fastening members are turned in one position they engage the standard 29 thereby fixing the same securely to the member 32. 95

When the toy is to be used as a carriage the front wheel 17 is adjusted by means of the slide 20 and the rear wheels 31 are adjusted by means of the rod 28 so that the seat 10 is substantially in a horizontal position. The child then sits on the seat 10 and propels the carriage with his feet and steers the same by means of the handle 26. When the toy is to be used as a rocker, the steering post 15 is adjusted axially by means of the 100 slide 20 in the position shown in Fig. 2. The members 33 are also rotated to a position which will allow the standard 29 to be free from the member 32 and also free to rotate about the pin 28 as the child rocks the toy. 105 The child then sits on the seat 10 places his feet on the rod 14^a and by grasping the han- 110

dle 26 a swinging motion of the body will rock the toy while the standard 29 rocks through small arcs about the pin 28 as the rear wheels 31 travel along the ground with 5 a reciprocating motion.

I would state in conclusion that while the illustrated example constitutes a practical embodiment of my invention, I do not limit myself strictly to the mechanical details 10 herein illustrated, since manifestly the same can be considerably varied without departure from the spirit of the invention as defined in the appended claims.

Having thus described my invention, I 15 claim as new and desire to secure by Letters Patent:

1. A toy rocker-carriage comprising a seat, means associated with said seat adapted to permit said seat to be rocked, means as- 20 sociated with said seat adapted to permit said carriage to be propelled along the ground, and a steering post journaled in said carriage for steering said carriage as it is propelled along the ground, said steering post being provided with means for adjusting said post in a plurality of vertical positions relative to said seat.
2. A toy rocker-carriage comprising a seat, a frame supporting said seat, a plu- 30 rality of rockers associated with said frame, a standard pivoted to said frame, a plurality of wheels journaled on said standard, means

for adjusting said standard in a plurality of positions relative to said seat, means for preventing the rotation of said standard 35 about its pivot, a wheel associated with said carriage adapted for steering, and means for adjusting said wheel in a plurality of positions relative to said seat.

3. A toy rocker-carriage comprising a 40 seat, a frame supporting said seat, a plurality of rockers associated with said frame, a plurality of wheels associated with said carriage, means for adjusting said wheels in a plurality of positions relative to said seat, 45 a steering post journaled in said carriage, one or more wheels journaled on said steering post, and means for adjusting the last mentioned wheel or wheels and said steering post in a plurality of positions relative to 50 said seat.

4. A toy rocker-carriage comprising a seat, a plurality of rockers associated with said seat, a plurality of wheels associated with said seat, adjusting means adapted to 55 permit said seat to be rocked on said rockers or propelled along the ground on said wheels, and a steering post associated with said carriage adapted to steer said carriage as it is propelled along the ground, said 60 steering post being provided with means for adjusting said post in a plurality of vertical positions relative to said seat.

FRANK HUMPHREVILLE.
